CRACKING OF HYDROCARBON OILS

James A. Wales, Westmount, Quebec, Canada,
assignor to McColl-Frontenac Oil Co. Limited,
Montreal, Quebec, Canada

Application April 12, 1935, Serial No. 15,981
In Canada April 2, 1935

4 Claims. (Cl. 196—49)

This invention relates to an improved process for converting relatively heavy or inferior hydrocarbon oils into lower boiling point products of a more valuable nature, the principal objects 5 being to obtain an increased yield of the lower boiling point products and to improve the characteristics of the relatively heavier residual products obtained therewith.

The improved process comprises passing the oil 10 through a suitable primary heating zone to a primary vaporizing zone where the reaction products are separated into vapors and residue, subjecting the vapors to primary and secondary fractionation thereby forming primary reflux condensate and a relatively lighter secondary reflux condensate, commingling the primary reflux condensate with the residue in the primary vaporizing zone, passing the secondary reflux condensate through a secondary heating zone and then 15 commingling it with mixed primary reflux condensate and residue drawn from the primary vaporizing zone, passing the so commingled products into a suitable reaction zone, passing liquid and vaporous reaction products from said reaction zone to a secondary vaporizing zone, commingling vapors from the secondary vaporizing zone with vapors from the primary vaporizing zone and subjecting the commingled vapors to the aforesaid primary and secondary fractionation and finally condensing the dephlegmated 20 vapors.

This process, subject to observance of suitable temperature and pressure conditions hereinafter specified, produces an exceptionally high yield 25 of relatively light hydrocarbons due to the secondary cracking to which the residue from the primary vaporizing zone is subjected when commingled, in the reaction chamber, with reaction products from the secondary heating zone. This 30 secondary cracking of the heavy residue from the primary vaporizing zone also produces, as residue from the secondary vaporizing zone, a product which has a lower viscosity for an equivalent gravity than residue produced by 35 prior cracking processes. This lower viscosity is a desirable property and represents a definite improvement in quality. The reaction products from the reaction chamber are fed to a secondary vaporizing zone in order to make possible 40 the removal of the then highly cracked relatively heavy hydrocarbons in the residue from this zone. This is desirable since further cracking of such residue would result in coke formation.

In carrying out the improved process it is contemplated that residual oil withdrawn from the

secondary vaporizing zone may be subjected to further fractionation and the condensed vapors returned to the system commingled with the raw oil and/or as reflux to the primary and/or secondary fractionating zones. It is also contemplated that a portion of the residual oil withdrawn from the primary vaporizing zone may, if desired, be cooled and then fed to the lower section of the reaction chamber to prevent coke formation in this zone. In order to assist fractionation in the primary and secondary fractionating zones a portion of the secondary reflux condensate may be cooled and then introduced into the upper section of the primary fractionating zone and into an intermediate section of the secondary fractionating zone. Fractionation in the secondary zone may be further assisted by returning to the upper section of this zone a portion of the condensed dephlegmated vapors derived therefrom.

Proceeding now to a more detailed description reference will be had to the accompanying drawings, in which

Figure 1 is a diagrammatic representation of one form of apparatus which may be used in carrying out the improved process, and

Figure 2 is a view similar to Figure 1 but showing a slight modification.

In these drawings the primary heating zone is represented as a coil 10 contained in a suitable furnace 11. The raw oil is fed to this zone through supply line 1, valve 2, pump 3, line 4, heat interchanger 5, and line 6. During its passage through interchanger 5 the raw oil is heated by indirect heat exchange with relatively hot residual oil from vaporizing zone 30. Further heating of the oil to the desired conversion temperature under any desired pressure occurs in zone 18, from whence the oil passes, through line 12 and valve 13, to a primary vaporizing zone 14, preferably located in the lower section of fractionator 31. The vaporous products from zone 14 pass directly to fractionating zone 31. The primary reflux condensate formed in fractionating zone 31 commingles with residual products in zone 14 and is passed therewith through line 15, valve 16, pump 17, line 18, and valve 19 to the upper portion of reaction chamber 25. A portion of the oil in line 18 may be fed to the lower section of the reaction chamber through line 79 and valve 80 and may be cooled, if desired, by passing same through line 81, valve 82, cooler 83, line 84, and valve 85, into the reaction chamber.

Superatmospheric pressure conditions are preferably maintained in heating zone 10, vaporizing

zone 14, and fractionator zone 31. The pressures in zone 14 and fractionator 31 may be substantially equalized with each other and may be substantially equalized with or lower than the pressure in the heating zone 10.

The vaporous products from fractionator 31 pass through line 45 and valve 46 to further fractionation in the secondary fractionator 50. The relatively light desirable vapors are withdrawn from fractionator 50 through line 51 and valve 52 and subjected to condensation and cooling in condenser 53, products from which pass through line 54 and valve 55 to a suitable receiver 56, from whence uncondensable gases are released through line 57 and valve 58. The distillate collected in receiver 56 is withdrawn through line 59 and valve 60. A portion of this distillate may be pumped through line 61, valve 62, pump 63, line 64 and valve 65 to the upper section of fractionator 50 to assist fractionation of the vapors contained therein. The secondary reflux condensate formed in fractionator 50 is conducted therefrom through line 67, valve 68, pump 69, line 70 and valve 71 to a secondary heating zone 72 for further conversion. Zone 72 is represented as a heating coil contained in a suitable furnace 73 and is preferably heated to a more severe conversion temperature than that employed in the primary heating zone 10. From zone 72 the reaction products are conducted through line 74 and valve 75 into line 18 where they are commingled with mixed primary reflux condensate and residues drawn from the primary vaporizing zone 14 and pass therewith into the upper portion of reaction chamber 25. The pressure employed in the secondary heating zone 72 may be substantially the same or higher than that employed in chamber 25. The liquid and vaporous reaction products formed in chamber 25 are conducted therefrom through line 26 and valve 27 to a second vaporizing zone 30 which is preferably maintained under a substantially reduced pressure relative to that employed in chamber 25 and wherein vapors may separate from residual products.

In Fig. 1 vaporizing zone 30 is shown as a section of fractionator 31 with a solid dividing wall between it and vaporizing zone 14 to prevent commingling of the liquid residual products in zones 30 and 14. In this case the vapors from both zones 30 and 14 commingle as they pass to the fractionating zone 31.

In Fig. 2 vaporizing zone 30 is shown as a separate chamber from which the vaporous products are discharged through line 42 and valve 43 to commingle, in fractionating zone 31, with the vaporous products from zone 14.

Residual products formed in the secondary vaporizing zone 30 may be withdrawn therefrom through line 35, valves 36 and 37, heat interchanger 5, line 38 and valve 39 to further cooling and storage or may be withdrawn through line 35, valve 36, line 40 and valve 41 to any desired further treatment. In the latter instance the residual products withdrawn through line 40 and valve 41 may be delivered to a tertiary vaporizing zone and there separated into vaporous products and residue, the residue thus obtained being removed from the system and the vaporous products being subjected to dephlegmation and condensation and returned to the system with the raw oil charge and/or as reflux in the primary or secondary fractionating zones.

A portion of the secondary reflux condensate from fractionator 50 may be passed from line 70

through line 91, valve 92, cooler 93, line 94 and valve 95 to the upper section of fractionator 31 to assist fractionation in this zone. If desired a portion of the secondary reflux condensate supplied to line 94 may be conducted therefrom through line 96 and valve 97 to an intermediate section of fractionator 50 to assist fractionation in this zone.

In the primary heating zone 10 the oil is preferably heated to conversion temperatures ranging from 850° F. to 920° F. under pressures ranging from 100 to 350 lbs. per square inch. In the secondary heating zone 72 the reflux condensate derived from the secondary fractionating zone is preferably subjected to conversion temperatures ranging from 900° F. to 1200° F. under pressures ranging from 150 to 750 lbs. per square inch. The pressure in the reaction chamber may be equal to or lower than the pressure in the secondary heating zone. The pressure in the primary and secondary vaporizing zones may be substantially the same as the pressure in the primary heating zone which is preferably substantially lower than the pressures employed in the reaction chamber and in the secondary heating zone. The pressure in the fractionating, condensing and collecting systems may be substantially equalized with the pressure in the vaporizing zones. The pressures in these zones preferably range from approximately atmospheric to maximum pressures of approximately 200 lbs. per square inch. It may be stated, however, that the range of temperatures and pressures mentioned herein is subject to considerable variation, it being possible to operate this process with pressures ranging from substantially atmospheric to higher pressures in the neighborhood of 2000 lbs. per square inch and with conversion temperatures ranging from a minimum of approximately 800° F. to a maximum of approximately 1200° F.

The following is a specific example of the operation of the process when using a 27° A. P. I. East Texas topped crude as the raw oil which is supplied to the system through the supply pipe 1:—

A temperature of 870° F. and a pressure of 150 lbs. per square inch are maintained in the primary heating zone. This pressure is substantially equalized in the vaporizing, fractionating, condensing and collecting zones. Relatively light reflux condensate from the secondary fractionator of the system is subjected in the secondary heating element to a temperature of approximately 930° F. under a super-atmospheric pressure of about 600 lbs. per square inch. The pressure in the reaction chamber is substantially equalized with the pressure in the secondary heating element. The residual relatively heavy oil which has passed once through the primary heating zone is commingled with the reflux condensate from the primary fractionating zone and is collected in the primary vaporizing zone at a temperature of about 800° F. and is then subjected to further conversion by being heated to about 870° F. by being commingled with the heated products from the secondary heating zone and then passing through the reaction chamber under conversion conditions. The commingling of these two streams of oil and vaporous products has the further desirable effect of preventing coke formation in the reaction chamber. The oil and vapors from the reaction chamber discharge at a superatmospheric pressure of about 150 lbs. per square inch into a secondary vaporizing zone, the vaporous products from which may commin-

gle with the vaporous products from the primary vaporizing zone in the primary fractionating zone. The residual products from the secondary vaporizing zone may pass from the system at 5 a temperature of about 800° F. through a heat exchanger or may pass to a further vaporizing chamber, the vaporous products from which may be condensed and returned to the system commingled with the raw oil charge or as reflux in 10 the primary or secondary fractionating zones. The residual product after cooling is a marketable fuel oil. This operation may yield approximately 55% of motor fuel having an anti-knock value of about 69 by the C. F. R. motor method. 15 In addition about 37% of marketable fuel oil may be produced, the other products being uncondensable gas and relatively small percentage of coke or carbonaceous material.

Having thus described my invention, what I 20 claim is:—

1. A hydrocarbon raw charging stock cracking process which comprises passing the oil through a suitable primary heating zone to a primary vaporizing zone where the reaction products are 25 separated into vapors and residue, subjecting the vapors to primary and secondary fractionation thereby forming primary reflux condensate and a relatively lighter secondary reflux condensate, commingling the primary reflux condensate with 30 the residue in the primary vaporizing zone, passing the secondary reflux condensate through a secondary heating zone and then commingling it with mixed primary reflux condensate and residue drawn from the primary vaporizing zone, 35 passing the so commingled products through a suitable reaction zone where further cracking of the mixed primary reflux condensate and residue is effected under conditions tending to prevent coke formation, passing liquid and vaporous reaction products from said reaction zone to a 40 secondary vaporizing zone, commingling vapors from the secondary vaporizing zone, with vapors from the primary vaporizing zone and subjecting the commingled vapors to the aforesaid primary and secondary fractionation and finally condensing the dephlegmated vapors.

2. A hydrocarbon raw charging stock cracking process which comprises heating the oil in a primary heating zone to cracking temperature under 45 pressure, discharging the heated oil to a primary

vaporizing zone maintained under substantially the same or lower pressure conditions, subjecting the vapors from the primary vaporizing zone to primary and secondary dephlegmation thereby forming primary reflux condensate and a secondary lighter reflux condensate, commingling said primary reflux condensate with the residue in the primary vaporizing zone, passing the secondary reflux condensate through a secondary heating zone in which said condensate is heated 10 to a higher cracking temperature under pressure, commingling the said mixed residue from the primary vaporizing zone with the reaction products from the secondary heating zone, passing such commingled products into the upper portion of 15 an enlarged reaction zone there effecting further cracking of the mixed residue from the primary vaporizing zone by direct heat interchange with the reaction products from the secondary heating zone and under conditions tending to retard 20 coke formation, delivering the liquid and vaporous reaction products from the lower portion of the reaction zone into a secondary vaporizing zone maintained under lower pressure than the reaction zone, separating the reaction products 25 into vapors and residue in the secondary vaporizing zone, removing said residue from the system, commingling said vapors with the vapors from the primary vaporizing zone and subjecting them to the aforementioned primary and secondary 30 dephlegmation and finally condensing the dephlegmated vapors.

3. A hydrocarbon oil cracking process as set forth in claim 2 in which a portion of the mixed residue withdrawn from the primary vaporizing 35 zone is delivered to the lower portion of the reaction chamber without previous commingling with the reaction products from the secondary heating zone, to assist in preventing coke, formation in said reaction chamber.

4. A hydrocarbon oil cracking process as set forth in claim 2 in which a portion of the mixed residue withdrawn from the primary vaporizing zone is cooled and then introduced into the lower portion of the reaction chamber without previous 40 commingling with the reaction products from the secondary heating zone, to assist in preventing coke formation in said reaction chamber.

JAMES A. WALES. 50
